TOY

Charles J. Bacon, Brooklyn, N. Y., assignor to The Spool Cotton Company, New York, N. Y., a corporation of New Jersey

Application February 9, 1933, Serial No. 655,865

3 Claims. (Cl. 46—37)

This invention relates to a novel and improved form of toy, the novel features of which will be best understood from the following description and the annexed drawings, in which I have shown selected embodiments of the invention and in which:

Fig. 1 is a front view of a sheet of material from which the toy may be formed;

Fig. 2 is a view similar to Fig. 1 but showing 10 the toy as completed;

Fig. 3 is an end view taken from the left-hand end of Fig. 1;

Fig. 4 is a view of a different embodiment but otherwise corresponding to Fig. 1;

Fig. 5 is a view corresponding to Fig. 3 but taken from the right-hand end of Fig. 4 after 15 the toy is completed;

Fig. 6 is another view corresponding to Fig. 1 but showing still another embodiment of the 20 invention;

Fig. 7 is a view corresponding to Fig. 2 and showing the completed toy of Fig. 6;

Fig. 8 is a view on the line 8—8 of Fig. 7;

Fig. 9 is a view on the line 9—9 of Fig. 7;

Fig. 10 is a view of the reverse side of one of 25 the wheel cut-outs.

The invention is particularly intended for the amusement of small children in an inexpensive manner, and with materials which are readily 30 available or obtainable. To that end, it comprises sheet material which may be cut or folded into appropriate representations of wheeled vehicles, the wheels being supplied by empty spools on which thread was originally wound.

In Fig. 1, for example, is shown a sheet 1 of 35 cardboard or the like having a slot 2 formed therein, this slot following generally the contour of the back and head of an elephant 3 depicted upon the face of the sheet. The elephant 40 is shown as drawing a cart 4 in which is a clown 5 driving the elephant by holding on to his tail. Another slot 6 is formed following generally the 45 contour of the clown's cap and connected to the slot 2 by sheet material along which extends a dotted line 7 with appropriate directions to "fold here".

In front of the elephant's head is shown a cut-out 8 fastened to the sheet at the spaced points 9, at which points the sheet material may be 50 readily cut or broken to remove the piece 8. Then, when the sheet is folded along the line 7, the locking tabs A and B may be interlocked, the point 10 of the tab A being received within the slot 11 of the tab B.

When the parts are thus assembled, the re-

sult is a pair of spaced folds 12 and 13, and these folds have therein openings 14 and 15 over which are closures 16. These closures may conveniently have on the face thereof an imitation of a label on the end of a spool of thread, and each closure may be detachably held in place over the opening at spaced points 17, as indicated. It will be seen that each opening 14 and 15 is generally circular in form and of more than 180° in extent or slightly less than 360°. Then when the shield 5 has been folded, or before that folding has taken place, the closures may be removed and then the openings are so arranged that they are in line with each other and a spool 18 may be placed through these aligned openings. The spool is 10 preferably of such size as to extend below the lower edge 19 of the sheet, as shown in Fig. 2, where it will be retained in place by means of the ears 20 formed by the removal of the closure.

The result of the above arrangement is a toy 20 which is pleasing to children and which is easily made of material readily available. For example, sets of toys may be furnished as advertisements for the sale of thread, and each toy may contain a different picture thereon, the different 25 pictures together being enough to form a circus parade. Preferably, the sheet material is provided with a suitable cut-out or push-out portion 21 over a hole through which a cord or thread 30 may be passed, whereby a toy may be drawn along the floor, the spool acting as a pair of wheels.

When the child is "playing circus" with the 35 toys, the closures 16 may be conveniently used as tokens of admission, and for that purpose the closure may be provided on its reverse side with a token such as indicated at 22 in Fig. 10. Similarly, the openings may be of different sizes to accommodate different sizes of spools, and the 40 wheeled vehicles depicted on the sheets will, of course, be varied to be appropriate for the various sizes of wheels. It is well known that spools of thread have designations contained on labels on the ends thereof indicating the kind of thread, and since the size of spool varies with the kind 45 of thread, said kinds of thread being wound on certain sizes of spool, the child playing with the toys will quickly learn what kind of thread it is necessary to buy to get the size spool needed for any particular toy.

In Figs. 4 and 5 is shown a slightly different 50 embodiment of the invention. In this case, the sheet has openings 23 and 24 spaced apart so as to indicate a four-wheeled vehicle, and placed in correct relation to that vehicle, which is indi- 55

cated generally at 25. Here again the sheet is adapted to be folded, as along the line 26, and when folded, the openings 23 and 24 are in line with openings 27 and 28, respectively, each of which is provided with closures as described above. In this form, no locking means is shown for fastening the sheets together, the spools alone being relied upon for this purpose.

Referring now to Figs. 6, 7, 8, and 9, I have shown therein a slightly different form of the invention. In this case, the picture designated generally at 29 is of a chariot with a driver and horse, and the chariot itself, while formed on the sheet 30, is made separately from the picture itself and then attached thereto. For example, the part of the sheet containing the chariot depicted thereon may be separated from the rest of the sheet, as along the lines 30, and, then folded, as indicated, to bring the parts 32 and 33 into parallel relation to each other, in which position they are locked by engagement of the tabs C and D. Openings 34 and 35 are provided covered with detachable closures as before, and when the folding has taken place as described above, these openings are in alignment so as to receive a spool 18. A suitable tab A on the sheet 30 may be inserted in the openings designated B to fasten the chariot to the combined horse and rider. The toy in this embodiment is therefore made up of two sheets, one of which with one or more spools would indicate a vehicle, and the other sheet, which can be detachably secured thereto, would indicate or represent objects which are appropriately associated with the vehicle.

From the above description, it will be seen that the invention is one which may be embodied in a variety of forms, some of which have been shown herein but others of which will readily suggest themselves to those skilled in the art.

For example, while the invention has been shown in connection with animal-drawn vehicles and

with automobiles, it may be applied to pictures or imitations of any other wheeled vehicle, as, for example, railroad trains or any other device having wheels. Therefore I do not intend to limit myself by the embodiments which I have shown and described, but only by the appended claims.

I claim:

1. A toy blank of sheet material having a wheeled vehicle depicted thereon and an opening disposed in a place where a wheel of said vehicle should appear in the picture, said opening being of a size to loosely receive a thread spool therein whereby such a spool may act as a wheel for the toy, and an easily separable closure connected to said sheet and closing said opening, said closure having on the front side thereof a label corresponding to the label on the end of a spool of thread.

2. A toy formed of sheet material and having parts adapted to be folded along indicated lines, said parts when so folded having aligned openings therein of generally circular form and adapted to receive a thread spool therethrough, one of said folds having thereon a picture of a wheeled vehicle so arranged with respect to one of said openings that the spool in that opening appears as a wheel of said vehicle, and means for detachably holding such a spool in position in said aligned openings.

3. A toy of sheet material having a wheeled vehicle depicted thereon and an opening disposed in a place where a wheel of said vehicle should appear in the picture, said opening being of a size to loosely receive a thread spool therein whereby said spool may act as a wheel for the toy and also being more than 180° in extent, whereby said spool may be forced into the opening and loosely held therein by the sheet material, in all positions of the toy.

CHARLES J. BACON. 40
